UNITED STATES PATENT OFFICE.

FELIX JOSEF JULIUS LECHLEDER, OF BROOKLYN, NEW YORK.

SMOKING-PIPE ATTACHMENT.

Application filed April 12, 1926. Serial No. 101,526.

The invention relates to smoking pipes and has for its object to provide an attachment for smoking pipes which employs a cap to enclose the bowl of the pipe thereby preventing sparks from flying from the bowl when the tobacco in the pipe is lighted.

Another object of the invention is to provide the bowl with an adjustable tamper for pressing down the tobacco in the bowl.

10 Still another object of the invention is to provide means by which the tamper is resiliently held in adjusted position relative to the cap and bowl.

15 Additional objects of the invention will appear in the following specification in which the preferred form of the invention is described.

20 In the drawings similar reference characters refer to similar parts in all of the figures, in which—

Figure 1 is a view showing my attachment adjusted on the bowl of a pipe;

Figure 2 is a side sectional elevation of Figure 1; and

25 Figure 3 is an enlarged sectional view on line 3—3 of Figure 2.

By referring to the drawings it will be seen that a cap 5 is employed which is normally disposed on the bowl 6 of the pipe 7.

30 This cap 5 has an orifice 8 through which a spindle 9 is disposed, a tamper 10 being mounted on the lower end of the spindle 9, the said tamper being disposed in the bowl 6 of the pipe 7 so that it may be employed 35 to press the tobacco down which is contained in the said pipe bowl 6.

At the upper end of the spindle 9 there is a knob or button 11 and disposed around the spindle 9 between the tamper 10 and the 40 knob or button 11 there is a spiral spring 12 which serves as a thread for the spindle 9. This is possible inasmuch as the diameter of the orifice 8 is not sufficiently large to permit the spiral spring 12 to pass longitudinally

45 therethrough except by turning the spiral spring 12 which then acts as a thread. The ends 13 and 14 of the spiral spring 12 press against the spindle 9 so that the rotation of the spiral spring 12 relative to the spindle 9 is retarded or prevented. Therefore, it will 50 be seen that by turning the knob or button 11 the spindle 9 will be rotated and with this

rotation the spiral spring 12 will also rotate and pass through the orifice 8 thereby adjusting the spiral spring 12 relatively to the 55 cap 5 at its orifice 8.

The spiral spring 12 serves to hold the spindle 9 and tamper 10 resiliently in adjusted position relatively to the cap 5 and the spindle 9 may be adjusted longitudinally 60 relatively to the cap 5 by turning the knob or button 11, thereby adjusting the spindle 9 through the spiral spring 12 which, as has been stated, acts as a thread. Therefore, the position of the spiral spring 12 when it 65 is raised may be adjusted relatively to the cap 5 and by this means the spindle 9 with its tamper 10 may be held resiliently in adjusted position. By pressing down on the knob or button 11 the tamper 10 will press 70 down the tobacco in the pipe bowl 6 but the spiral spring 12 will raise the spindle 9 and the tamper 10 and the distance which the spindle 9 with its tamper 10 will be raised will depend on the position of the 75 spiral spring 12 relatively to the cap 5 at its orifice 8.

The orifice 8 in the cap 5 is slightly larger than the spindle 9 but not sufficiently large to permit the spiral spring 12 to pass 80 therethrough without rotation and the smoke will, therefore, pass through the orifice 8 around the spindle 9 but additional openings may be made in the cap 5 as may be desired.

When my attachment is used sparks will 85 be prevented from flying from the pipe bowl 6 when the tobacco in the said pipe bowl 6 is lighted but nevertheless the pipe may be smoked in the usual way and with my tamper 10 it is always possible for the smoker to 90 press down the tobacco in the pipe bowl 6 after which the tamper will be moved away from the tobacco in the pipe bowl because of the resiliency of the spiral spring 12.

95 What I claim is:—

1. In an attachment for a smoking pipe having a bowl, a cap for the bowl having an orifice, a tamper having a spindle extending through the orifice, and resilient means adjustably held relatively to the cap 100 for holding the spindle yieldingly in position relatively to the cap.

2. In an attachment for a smoking pipe having a bowl, a cap for the bowl having an

orifice, a tamper having a spindle disposed in the orifice, a spiral spring disposed around the spindle arranged to retard its rotary movement relatively to the spindle, the spring serving as a thread for the spindle which meshes with the cap at the orifice therein by which means the spindle may be

rotated relatively to the cap to adjust the position of the tamper relatively to the cap for holding the tamper yieldingly as desired relatively to the cap and means to limit the movement of the terminals of the spiral spring longitudinally of the spindle.

FELIX JOSEF JULIUS LECHLEDER.
